[57] CLAIM

The ornamental design for a boat hull protector, as shown and described.

DESCRIPTION

FIG. 1 is an isometric view from the top, rear and left side of a boat hull protector, showing my new design;

FIG. 2 is an isometric view from the bottom, rear and left side thereof;

FIG. 3 is a left side elevational view thereof; the right side, not shown, is a mirror image of the left side; and,

FIG. 4 is an enlarged fragmentary isometric view from the top, front and left side thereof.
